UNITED STATES PATENT OFFICE.

HORACE H. HASTINGS, OF NEW YORK, N. Y.

HYDROCARBON-BURNER.

1,303,662.

Specification of Letters Patent. Patented May 13, 1919.

Application filed October 6, 1917. Serial No. 195,156.

To all whom it may concern:

Be it known that I, HORACE H. HASTINGS, a citizen of the United States, residing at New York, in the county of New York and 5 State of New York, have invented certain new and useful Improvements in Hydrocarbon-Burners; and I do hereby declare the following to be a full, clear, and exact description of the invention, such as will enable others skilled in the art to which it 10 appertains to make and use the same.

My invention has for its object to provide an improved hydrocarbon burner adapted for use in cooking stoves, furnaces, heaters, 15 and in fire pots of the large steam generating boilers.

The present invention is in the nature of a modification of, or improvement on the hydrocarbon burner disclosed and claimed 20 in my prior Patent 1,199,177, of date, September 26, 1916, and provides certain improved features which very materially improve the action of the burner by way of greater heating efficiency, more complete 25 combustion of the hydrocarbon and resulting economy in the use of fuel. The means by and manner in which these improved results are accomplished, will be fully disclosed in the following description of the 30 commercial form of the improved burner.

In the drawings which illustrate the burner, like characters indicate like parts throughout the several views.

Referring to the drawings,

35 Figure 1 is a view chiefly in vertical section but with some parts in full, showing the improved burner applied to a heater of the water or steam heating system;

Fig. 2 is an enlarged vertical section taken 40 on the line 2—2 of Fig. 1; and

Fig. 3 is a horizontal section taken on the line 3—3 of Fig. 2.

The numeral 4 indicates the hot water 45 heater, as an entirety, the same being of the usual or any approved construction.

In the application of my improved burner, to the fire box or combustion chamber of this boiler, the customary coal grate is removed and a large air intake tube 5 is extended through what is usually the ash pit door opening and has an upturned end that terminates at the lower central portion of the combustion chamber 4^a of the heater.

Seated on and fitted to the upturned in-

ner end of the air intake tube 5 is a base 55 plate 6 which has a large central opening 7 and surrounding air passages 8, which latter, as shown, are four in number. A metal bowl 9, preferably a casting, formed independently of the base plate 6, is seated in the 60 opening 7 and has a flanged upper edge that rests upon the base plate 6 so as to thereby support the bowl while permitting independent expansion and contraction of the said bowl and base plate. This bowl 9 has 65 an independent gas chamber 10 and has several, as shown two, upwardly projected gas nozzles 11 that are preferably conical in form and are provided with radiating perforations in their side walls. The lower 70 ends of these nozzles 11 are in open communication with the gas chamber 10. A gas supply pipe 12 leads to the gas chamber 10, through the air tube 5, and from a point exterior of the heater and at its outer portion, 75 is provided with a valve 13, by means of which it may be opened and closed, at will.

This burner is adapted to burn the heavier hydrocarbons and, in fact, will burn anything from crude oil to kerosene. A liquid 80 hydrocarbon is supplied to the burner from a suitable source, such as an elevated tank, not shown, through a so-called oil supply pipe 14, which, at the exterior of the heater, has a valve 15. This oil pipe 14 is extended 85 through the air intake tube 5, and its inner end is provided with branches 14^a that are extended upward through the gas chamber 10 and one axially through each of the gas nozzles 11 to points above the same. Preferably, and as shown, the upper ends of the branch tubes 14^a are threaded and screwed 90 through the upper ends of the nozzles 11. To the threaded upper ends of the branch tubes 14^a are attached the upper branches or 95 crowns of the so-called nozzle caps 16, that are preferably bell-shaped, or of conical form and surround the nozzles 11, but are spaced therefrom, so as to afford annular 100 passages between the two.

Overlying the bowl 9, and spaced vertically therefrom is a hollow shell or so-called superheating air chamber 17 that is closed at its top and has outwardly and downwardly curved or extended tubular legs 17^a, 105 as shown, four in number. The lower ends of these tubular legs 17^a rest upon the base plate 6 and register, one with each of the air

passages 8 thereof. To loosely aline the lower ends of the legs 17^a with the said ports 8, the base plate 6 is provided on top with U-shaped alining ribs 6^a which, while they 5 keep the said legs in proper alinement, as stated, allow the same to expand and contract independently of the said base plate. The air superheating chamber 17, in its bottom, is provided with air discharge ports 10 17^b that aline with and immediately overlie, but are spaced from the crowns of the respective nozzle caps 16.

I have found that the best results and great efficiency can be obtained by the use of 15 a small fan or blower arranged to work in the air intake tube 5. In the drawings, such a fan or blower is indicated by the numeral 18. The same is preferably applied in the outer or receiving end of the said tube, and 20 is secured to the armature shaft 19 of a small electric motor 20, which latter, by means of suitable brackets, is secured to a flanged bearing ring 21 detachably applied to the said tube 5, so that the motor and 25 fan and bearing ring may, as a self-contained structure, be applied to or removed from the said air tube.

Of course, the natural draft of the furnace would produce an intake of air through 30 the air tube but the use of the fan, positively insures this result and provides a predetermined draft. By using a variable speed electric motor, such as can be had in the market, the speed of the fan, and hence, 35 the force of the draft may be regulated at will.

Where city gas, for example, is available, I propose to use the same, not only to start 40 the burner into action, but to supply the nozzles 11 with a limited amount of gas which continues to burn to act as a pilot light to keep the nozzle pipe 16 and other metallic parts hot, when the supply of 45 hydrocarbon is cut off, and so that whenever the hydrocarbon is turned on, the generation of hydrocarbon gas and ignition thereof will be instantaneous.

Where this gas for maintaining the pilot light is not available, the burner will have 50 to be primed in starting; and this may be done by pouring a little kerosene or gasoline into the bowl 9 and igniting the same, so as to heat up the nozzle caps and other metallic parts, as required to effect the initial generation of the hydrocarbon gas.

When the nozzle caps and other metallic parts of the burner are once heated, the burning action will be as follows:

The hydrocarbon oil delivered from the 60 pipe 14 and through the branch pipes 14^a will flow from the upper ends of the latter onto the crowns of the nozzle caps 16 and will run down, or start to run down over the outer surfaces of the said caps. The air 65 supplied to support the combustion being de-

livéred through the hot tubular air legs 17^a and superheating chamber 17 will be delivered as a downward blast directly onto the crowns of the nozzle caps 16, and will there meet the overflowing hydrocarbon so 70 that the generation of hydrocarbon gas will be almost instantaneous and the resulting combustion which takes place will be entire and complete. The burning flames will be blown or dashed down into the bowl 9, and 75 being deflected, find a ready escape laterally and upward through the ample flame passages afforded between the tubular air intake legs 17^a. Thus the flames are caused to come into contact with all of the metal parts of 80 the burner and are dashed completely around the legs 17^a and against the sides and over the top of the superheating chamber 17, and from thence, complete the combustion within the combustion chamber 4^a 85 and outlet passages of the heater.

When the pilot burner is kept in action, the amount of city gas used may be reduced to a very small amount so that the cost thereof is very small. Of course, when desired, the city gas or gas affording the gas supplied to the nozzles 11 may be cut off when once the burner is started into action, and the generating of hydrocarbon gas from the oil is properly started.

I very greatly improve the action resulting from the manner in which the superheated air which supports the combustion is delivered in a downward direction, or against the crowns of the so-called nozzle caps, and hence, this arrangement, it will be understood, is highly important, regardless of whether or not the gas nozzles within the nozzle caps are or are not employed.

The burner herein disclosed and claimed 105 has not only been put into use and found efficient, but has been commercially put on the market, and in the use thereof, it is found that in large, as well as in small heating plants or boilers, by the use of low grade 110 hydrocarbons, greater heating effect to unit of cost is attained than can be attained by the use of coal in the ordinary commercial furnaces and boilers.

The term "heater" is used in a broad and 115 liberal sense, and, obviously, will include the heat generating chambers of all kinds of stoves, furnaces, and boilers, wherein heat is generated by combustion of oil or other combustible fluid.

What I claim is:

1. In a burner of the character described, the combination with an air intake tube, of an oil pipe delivering at the delivery end of said air tube and having a nozzle cap at its 125 delivery end, an air superheating chamber overlying said nozzle cap and receiving air from said air tube and delivering the same directly downward against said nozzle cap, and a gas delivery nozzle located within said 130

nozzle cap and having connections for supplying gas thereto.

2. In a burner of the character described, the combination with an air intake tube having a base plate at its upper delivery end, a bowl centrally seated in said base plate, said base plate having air passages circumferentially spaced around said bowl, an oil delivery pipe extended through said bowl and provided at its delivery end with a depending nozzle cap, and an air superheating chamber located above said nozzle cap, provided with tubular legs registering with the air passages of said base plate, and having in its bottom an air port located above and arranged to deliver the superheated air directly downward against said nozzle.

3. In a burner of the character described, the combination with an air intake tube having a base plate at its upper delivery end, a bowl centrally seated in said base plate, said base plate having air passages circumferentially spaced around said bowl, an oil delivery pipe extended through said bowl and provided at its delivery end with a depending nozzle cap, and an air superheating chamber located above said nozzle cap, provided with tubular legs registering with the air passages of said base plate, and having in its bottom an air port located above and arranged to deliver the superheated air directly downward against said nozzle cap, the said bowl having a perforated gas nozzle located within but spaced from said nozzle cap.

4. In a burner of the character described, the combination with an intake tube having a base plate at its upper delivery end, a bowl centrally seated in said base plate with freedom for independent expansion and contraction, said base plate having air passages circumferentially spaced around said bowl, a fluid fuel delivery pipe extended upward through said bowl and provided at its delivery end with a depending nozzle cap, and an air superheating chamber located above said nozzle cap, provided with tubular legs loosely registering with the air passages of said base plate, said chamber in its bottom, having an air port located above and ar-

ranged to deliver the superheated air directly downward against said nozzle cap.

5. In a burner of the character described, the combination with an air intake tube having a base plate at its upper delivery end, a bowl centrally seated in said base plate, said base plate having air passages circumferentially spaced around said bowl, a multiplicity of fluid fuel delivery pipes extended through said bowl and provided at their upper ends with depending nozzle caps, said bowl having a depending gas chamber and perforated gas nozzles extended upward therefrom into but spaced from said nozzle caps, and an air superheating chamber located above said nozzle caps, provided with tubular legs registering with the air passages of said base plate, said chamber, in its bottom having air ports located above and arranged to deliver the superheated air directly downward against the respective nozzle caps.

6. In a burner of the character described, the combination with an air intake tube having a base plate at its upper delivery end, a bowl centrally seated in said base plate, said base plate having air passages circumferentially spaced around said bowl, a multiplicity of fluid fuel delivery pipes extended through said bowl and provided at their upper ends with depending nozzle caps, said bowl having a depending gas chamber and perforated gas nozzles extended upward therefrom into but spaced from said nozzle caps, an air superheating chamber located above said nozzle caps, provided with tubular legs registering with the air passages of said base plate, said chamber, in its bottom, having air ports located above and arranged to deliver the superheated air directly downward against the respective nozzle caps, and means for producing a forced inflow of air through said air tubes and superheating chamber and against said nozzle caps.

In testimony whereof I affix my signature in presence of two witnesses.

HORACE H. HASTINGS.
